UNITED STATES PATENT OFFICE.

JOSEPH W. REED, OF KALAMAZOO, MICHIGAN.

STEAM-SUPERHEATER.

SPECIFICATION forming part of Letters Patent No. 310,225, dated January 6, 1885.

Application filed July 25, 1884. (No model.)

To all whom it may concern:

Be it known that I, JOSEPH W. REED, a citizen of the United States, residing at Kalamazoo, county of Kalamazoo, State of Michigan, 5 have invented a new and useful Steam-Superheater, of which the following is a specification.

This invention has for its leading object a construction and arrangement of parts where-
10 by the waste steam from the cylinder is circu-
lated through the smoke-box of a steam-boiler,
or an equivalent heated chamber of a steam-
boiler, wherein said steam is superheated and
thence passed into the steam-chest for reuse.

15 A construction embodying this invention
consists in a pipe leading from the cylinder
waste-ports, passing well into the smoke-box,
and from thence leading to and connecting with
the steam-chest of said cylinder.

20 Detailed peculiarities of the constructions of
parts are hereinafter described.

In the drawings, forming a part of this
specification, Figure 1 is a broken end elevation
25 in cross-section on a line near the vertical center; Fig. 2, a broken horizontal section, cer-
tain parts being left full; Fig. 3, an enlarged
perspective of parts in Figs. 1 and 2; Fig. 4,
an enlarged plan of parts in Fig. 2; and Fig.
30 5 is a rear end view of the cylinder and steam-
chest at the right of Fig. 1 enlarged.

This invention is illustrated in duplicate as
connected with a locomotive-engine, the cylinders C' C and steam-chests H H of which are
35 in duplicate, as in Fig. 1; but the invention is
applicable to a single engine as well, either
stationary or portable; hence the parts of the
invention will be described in the singular
number.

40 The smoke-box B of a boiler is necessarily
heated by the heat which passes therein out of
the forward end of the boiler-flues c, and for
this reason I locate the superheating device in
said box. The cylinder-cocks i i are connected
45 by a pipe, r, provided with a T-coupling, e.
A pipe, u, connects with this coupling and
with the heater-pipe v, located in the smoke-
box B. The upper end of the pipe v connects
50 in the upper portion of the smoke-box. A
heater-pipe, h, connects with the heating-

chamber R and passes out of the smoke-box
connecting with the steam-chest H. The up-
per ends of the heater-pipes v h might form
immediate connection with each other, and 55
thus dispense with the heating-chamber R;
but I prefer to use said chamber. The pipe
u v is provided with a cock, y.

t is a crank connecting therewith. This
crank t is connected with a pivoted lever, T, 60
by a pivotally connecting-rod.

x is a rod pivotally connected with the up-
per end of the lever T, (here shown broken,)
but which in use would be extended to the
cab or other convenient place in reach of the 65
operator.

The construction is provided with check-
valves at a", a', and i i. The cock y performs
the office of the cocks usually located at the
ports i i of the cylinder. 70

In the operation, when the engineer opens
the cock y by means of the crank t and con-
necting means, the waste steam and water from
the ends of the cylinder are forced through
pipes u v into the heating-chamber R and pass 75
on thence through pipe h into the steam-chest
H, the same being superheated during said
passage by the heat in the smoke-box B. By
this means the lubricant used in the steam
chest and cylinder is conveyed through the 80
superheater with the steam back into the
steam-chest again, thus by a continuous reuse
effecting economy and a better working of the
engine. The objectionable noise of escaping
steam from the cylinder-cocks is obviated and 85
the power of the engine improved. The
check-valve a" prevents a return of steam into
pipe u, and the check-valve a' opens to admit
the superheated steam into the steam-chest
when the pressure is less in said chest than 90
the pressure in pipe h, thus preventing the
exit of any steam from the steam-chest into
pipe h. I prefer to make the heater-pipe v
spiral, as in Figs. 1 and 2, thus securing a
greater heating capacity, as the passage of 95
steam is slower. The heating-chamber R is
provided with vent-pipes n n, terminating be-
low the mouth of the exhaust-pipe D, near the
exhaust-ports a a of the engine. These vents
relieve the heater-chamber R in case of an un-
due pressure of steam, and thus facilitate the 100
passage of the steam through the superheater.

The heater-chamber R is provided with an under extension, f, into which any sediment therein may settle, and which may be cleaned out by removing the plug d.

5 P P are the pipes which convey steam from the boiler into the steam-chests. A steam-gage is shown at S for testing the degree of steam-pressure in the superheater.

Having thus described my invention, what 10 I claim as new is—

1. The combination of a steam-chest, a cylinder, a smoke-box, and pipes leading from the cylinder to the steam-chest, and passing through the smoke-box and formed spiral in 15 said box, substantially as set forth.

2. The combination of a steam-engine cylinder, steam-chest, smoke-box, and spiral pipes connecting the steam-chest and cylinder-ports and passing through the smoke-box, 20 said pipes being provided with suitable cocks and check-valves, substantially as set forth.

3. The combination, with the cylinder and steam-chest of a steam-engine, of a steam-heating chamber suspended in the smoke-box 25 of the boiler, said chamber provided with

vent-pipes and pipes connecting with the steam-chest and cylinder and with said steam-heating chamber, all substantially as set forth.

4. The combination, with a steam-heating chamber suspended in the smoke-box of a 30 steam-boiler, of a steam-chest and cylinder, a pipe provided with the spiral portion leading from the cylinder to said chamber, and a pipe leading from said chamber to the steam-chest, substantially as set forth.

5. The combination, with a cylinder and steam-chest of an engine, of a steam-heating chamber suspended in the smoke-box of the boiler, said chamber provided with the under extension, vent-pipes connecting therewith, 40 and pipes connecting said chamber and cylinder and steam chest, all substantially as set forth.

In testimony of the foregoing I have hereunto subscribed my name in presence of two 45 witnesses.

JOSEPH W. REED.
